UNITED STATES PATENT OFFICE.

GEORGE O. HILTON, OF DETROIT, MICHIGAN, ASSIGNOR TO THE IDEAL MANUFACTURING COMPANY, OF DETROIT, MICHIGAN, A CORPORATION OF MICHIGAN.

FLUSHING-VALVE.

1,004,650.

Specification of Letters Patent.

Patented Oct. 3, 1911.

Application filed December 2, 1909. Serial No. 531,040.

To all whom it may concern:

Be it known that I, GEORGE O. HILTON, a citizen of the United States of America, residing at Detroit, in the county of Wayne 5 and State of Michigan, have invented certain new and useful Improvements in Flushing-Valves, of which the following is a specification, reference being had therein to the accompanying drawings.

10 The invention relates to slow-closing valves of that type employed for use in connection with water-closets, and for other purposes where it is desired to maintain a flow for a limited period, and then to automatically cut off the same.

The invention consists in certain features of construction with particular reference to the means employed for variably timing the flow, means for insuring the operation of 20 the mechanism after the initial movement, in the means for controlling the after-flow, and other features, as hereinafter set forth.

In the drawings—Figure 1 is a central longitudinal section through the valve; Fig. 25 2 is a view of a portion of Fig. 1 showing the means for locking the control valve; Fig. 3 is a section on line X—X, Fig. 5; Fig. 4 is a view of a portion of Fig. 1 showing the flushing valve open, and Fig. 5 is a 30 view of a portion of Fig. 1 showing the flushing valve partially closed.

A is a casing constructed to have a central chamber B connected with the inlet passage C and a surrounding chamber D 35 connecting with the outlet passage E.

F is a cylindrical wall separating the chambers B and D, and H is a cup-shaped valve fitting over the wall F.

The valve H is carried by a flexible diaphragm I which is mounted in the casing between annular flanges respectively upon the casing A and a cap casing A' therefor. The valve is secured to the diaphragm by a central pin J, which also secures a disk seat 40 K and inner member L which engages the inner face of the wall F. Above the diaphragm I is formed in the casing A' a chamber M, which is connected by a bypass N with the chamber B. This bypass 45 comprises a channel N' in the casing A' terminating in a port in the annular flange thereof and a passage N² in the casing A, having its port registering with that of the passage N'. In the passage N² is located a

check valve O' and an adjustable valve P 55 preferably of the needle-type, which may be operated from outside of the casing A, and is normally protected by a removable cap Q.

Centrally above the chamber M a chamber R is formed in the casing A', which is connected by a passage S with the chamber D, or outlet E thereof. Between the chambers R and M is a valve seat T, which is normally closed by a conical valve U having 60 a vertically-extending stem U'.

V is a flexible diaphragm closing the upper end of the chamber R and secured by a cap V'.

W is a push button having its stem W' 70 extending through the cap V' and adapted to operate the stem U' of the valve U. As shown, this stem W' of the push button is hollow, and telescopically engages a pin X, which is secured to the diaphragm V and 75 stem U' and forms an upward extension of the latter.

With the construction as thus far described, the normal position of the valve is one in which the cup-valve H is resting 80 with its disk seat K upon the upper end of the cylindrical wall F. When it is desired to open the valve, the button W is depressed which by operating the control valve U' and forcing it from the seat T will open 85 communication between the chamber M and the chamber R. This will permit the water which is in the chamber M to pass first to the chamber R and thence through the passage S to the outlet passage E. Consequently, the pressure on the upper side of the valve H will be lowered, while the pressure upon the under side remains the same, thereby causing the lifting of the valve 90 from its seat and opening direct communication between the inlet passage C and the outlet passage E. When the main valve is thus opened, the flow will continue until the pressure in the chamber M, by reason of its bypass connection with the passage C, rises 95 to equal the pressure in the chamber B. As the upper side of the valve H has a greater surface area exposed to the pressure in the chamber M than the surface of the under side has exposed in the chamber B, when 100 the pressure in the chambers becomes equal the valve will be closed by the excess surface pressure on the upper side of the valve 105

together with the action of gravity and the spring Y which tends to retain the valve closed.

In the operation just described, the time in which the valve is open depends upon the time required for equalizing the pressures in the chambers B and M, and this in turn depends upon the restriction of the bypass N. The restriction may be varied by adjusting the valve P and as this is accomplished from outside of the casing, when the cap Q is removed, it is obvious that the valve may at any time be quickly set for any desired time of operation.

It is essential to the proper operation of the valve that the control valve U should remain open long enough to permit the discharge of the water from the chamber M and the upward movement of the diaphragm and valve H. I have, therefore, provided means automatically operating after the depression of the button W for locking the latter in its depressed position until the main valve is open. This locking mechanism consists of a latch Z, which is pivotally secured to a member Z', which secures the seat T in position in the casing. The latch Z normally extends into the path of the valve U and when the latter is depressed by the push button the hook Z² of the latch will engage with the flange of the valve and hold the latter from being returned by the tension of the spring R'. The parts remain in this position until the rise of the cup-shaped valve H presses the head of the pin J against the latch lever Z, causing the disengagement of the hook Z² from the valve U and permitting the latter to seat.

For use in connection with water-closets, it is necessary that subsequent to the flushing, and after the breaking of the siphon, a sufficient quantity of water be permitted to pass the valve to refill the bowl. With my improved construction, this refilling occurs after the cup-shaped valve H has again engaged with the upper end of the cylindrical wall F, but before it has moved sufficiently far down to bear against the seat K. The

first flow is checked the instant that the cup-shaped valve H and wall F engage, but after the valve moves slightly farther down a clearance is provided which permits a restricted flow, continuing until the seat K is reached. As shown, a clearance is provided by forming outwardly and inwardly-projecting beads F' and H' respectively upon the wall F and cup H. These beads engage with each other, but are limited in width so that when they pass from registration, there will be a clearance for the flow of water.

To govern the amount of after fill, I provide means for variably restricting the passage of the water. As shown, this com-

prises the members L and L' relatively rotatively adjustable upon the pin J. These members are provided with a series of ports L² L³ which may be adjusted into full registration or to any degree of restriction. The water from the chamber B must pass through these registering ports and, consequently, by proper adjustment the amount of water permitted to pass may be regulated as desired.

Where a number of flushing valves are connected with the water conduit, the operation of one will temporarily lower the pressure in the others by siphonic action. This might result in the setting into operation of the other valves, as the water will be drawn out from the chamber M through the passage N. If the pressure in the chamber B were quickly restored the valve H would be opened as the restricted passage N would not permit the pressure in the chamber M to be raised simultaneously with the raising of the pressure in the chamber B. To avoid this result the check valve O' is placed in the passage N and effectually prevents any movement of the water in a reverse direction through said passage—that is, from the chamber N toward the conduit C.

What I claim as my invention is:

1. In a flushing valve the combination of a vertically arranged casing having an opening at its top, an integral laterally extending tubular member within the casing terminating in a centrally arranged cylindrical part, said member being open at its respective ends, to constitute an inlet passage, an outlet passage surrounding the cylindrical part of said member, the wall of the casing having a vertically extending restricted opening communicating with a laterally extending opening leading into the inlet passage, an adjustable valve for the laterally extending opening, and said vertically extending opening being enlarged to provide a valve seat, a check valve positioned on said seat, a diaphragm extending over the top of the casing and having an opening registering with the vertically extending opening and an auxiliary opening registering with the outlet passage, a valve carried by the diaphragm for the outlet passage, a cover for the casing, and an auxiliary valve controlling the passage through the diaphragm to the outlet passage.

2. In a flushing valve the combination of a vertically arranged casing having an opening at its top, an integral laterally extending tubular member within the casing terminating in a centrally arranged cylindrical part, said member being open at its respective ends, to constitute an inlet passage, an outlet passage surrounding the cylindrical part of said member, the wall of the casing having a vertically extending

restricted opening communicating with a laterally extending opening leading into the inlet passage, an adjustable valve for the laterally extending opening, and said vertically extending opening being enlarged 5 to provide a valve seat, a check valve positioned on said seat, a diaphragm extending over the top of the casing and having an opening registering with the vertically extending opening and an auxiliary opening 10 registering with the outlet passage, a cup-shaped valve projecting downwardly from the diaphragm and engaging over the cylindrical part of the inlet passage, integral 15 guides on the casing for said valve, a cover for the casing and an auxiliary valve controlling the passage through the diaphragm to the outlet passage.

3. The combination of a casing having a 20 central water inlet passage and a surrounding outlet passage with an annular valve seat therebetween, a cup shaped valve for engaging said seat to close communication between said passages, a diaphragm carrying 25 said valve, said valve having a variably restricted opening, a water-pressure chamber on the side of said diaphragm opposite said seat having a restricted passage connecting the same with said water inlet passage, a 30 control valve for exhausting the water from said chamber, operating means for seating said control valve, a spring actuated pivoted latch for engaging said control valve when unseated to hold the same from closing, and 35 means operated by the opening of said main valve for disengaging said latch.

4. The combination with a casing, having a central inlet, a surrounding outlet and an annular valve seat therebetween; a cup-shaped 40 valve for engaging said valve seat, a diaphragm carrying said valve, a water-pressure chamber on the side of said diaphragm opposite said seat, a restricted passage connecting said water-pressure chamber with 45 said inlet passage, an adjustable valve within said passage, a control valve for exhausting the water from said pressure chamber, said control valve having a lateral projection, means for automatically closing said 50 control valve, a spring held latch having an overhanging shoulder for engaging said projection on the control valve when opened to temporarily delay the reclosing of the same, and means operated by the opening of said 55 main valve for disengaging the latch.

5. The combination with a casing having an inlet passage and an outlet passage separated from each other by an annular valve seat, a cup-shaped valve for telescopically 60 engaging said seat, and a bead on the valve engaging the seat for closing communication between said passages upon the initial engagement of said cup-shaped valve in the closing movement thereof, said seat having 65 a reduced portion whereby in the further

movement of said valve a restricted clearance is provided, for the purpose described.

6. The combination of a casing having inlet and outlet passages, an annular valve seat separating said inlet and outlet 70 passages, and a cup-shaped valve for telescopically engaging said annular seat having a closing bearing upon the initial engagement with said seat, a final closing bearing on the end of said seat, and a clearance between 75 said bearings for forming a restricted opening intermediate the initial and final closings of said valve.

7. The combination of a casing having an 80 annular valve seat therein, a cup-shaped valve for telescopically engaging said seat having a bearing for engaging the end of the seat, and coöperating surfaces on said valve and seat for forming an initial closing, and providing a restricted opening during the 85 interval between the initial and final closing of the valve.

8. The combination with a casing provided with a valve seat, of a valve having an initial and a final closing engagement with 90 said seat, the coöperating surfaces of the valve and seat affording a restricted opening at one point in the movement of the valve, and means for varying the restriction of said intermediate opening. 95

9. The combination with a casing having a valve seat, of a valve for the seat, the coöperating surfaces of the valve and seat affording a restricted opening, and relatively 100 adjustable register slides for varying the restriction of said opening.

10. The combination with an annular valve seat, of a cup-shaped valve telescopically engaging said seat and having an initial and a final closing bearing upon said 105 seat with a clearance therebetween, and a concentric bearing on said valve for engaging said seat, having a variably restricted opening.

11. The combination with an annular 110 valve seat, of a valve having concentric portions telescopically engaging said seat inside and outside of the same, coöperating beads on said seat and one of said concentric portions of the valve for forming a closure 115 on the initial engagement of the valve, and means on the other of said concentric portions of the valve for forming a variably restricted opening therewith.

12. The combination with an annular 120 valve seat, of a cup-shaped valve telescopically engaging said seat, and having a bearing for engaging the end of the seat and a bearing for forming a closure on the initial telescopic engagement with said seat, there 125 being a clearance between said bearings, a ported member on said valve telescopically engaging the opposite side of said seat, and an adjustable member for variably restricting the ports of said ported member. 130

13. The combination of a casing having a central water inlet passage and a surrounding outlet passage with an annular valve seat therebetween, a valve for engaging said seat to close communication between said passages, a diaphragm opposite said seat having a restricted passage connecting the same with said water inlet passage, means for variably restricting said passage, a 5 check valve controlling the latter, a controlling valve for exhausting the water from said chamber, operating means for seating said controlling valve, said valve having a projecting engaging flange, a latch pivoted to

the controlling valve seat, and having an 15 overhanging shoulder for engaging said valve flange when unseated to hold the same from closing, and a spring for the controlling valve and means operated by the opening of said main valve for disengaging said 20 latch.

In testimony whereof I affix my signature in presence of two witnesses.

GEORGE O. HILTON.
